UNITED STATES PATENT OFFICE.

HENRY B. KEIPER, OF LANCASTER, PENNSYLVANIA.

TYUERE.

SPECIFICATION forming part of Letters Patent No. 391,474, dated October 23, 1888.

Application filed August 3, 1886. Serial No. 209,865. (No model.)

To all whom it may concern:

Be it known that I, HENRY B. KEIPER, a citizen of the United States, residing at Lancaster, in the county of Lancaster and State of Pennsylvania, have invented certain new and useful Improvements in Tuyere-Irons; and I do hereby declare the following to be a full, clear, and exact description of the invention, such as will enable others skilled in the art to 50 which it appertains to make and use the same.

The object of this invention is to do away with the necessity for bends and elbows in the pipes connecting tuyere-irons with fans which furnish the blast.

15 To this end my invention chiefly consists in the combination of an axially-movable tuyere-iron body and nozzle attached thereto, with a fixed cap or cover for said body, and clamping devices which secure them together but 20 allow the axial adjustment of said body, so as to present the nozzle to the connecting-pipe at any convenient direction. My invention further consists in certain additional features and details of construction, hereinafter particularly 25 set forth and claimed.

Figure 1 represents a plan view of the tuyere-iron embodying my invention. Fig. 2 represents a similar view of the body of said iron, the cover and draft-regulator having been removed. Fig. 3 represents a vertical section through the center of the complete tuyere-iron across the draft-regulator. Fig. 4 represents 30 a perspective view of the tuyere-iron taken from below; Fig. 5, a detail view of the draft-regulator, and Fig. 6 a detail view of the cinder-slide for the bottom of the tuyere-iron body.

A designates the cap, which covers the top of the tuyere-iron body B, the latter being provided immediately below said cap with horizontal flanges or ears b, having in them slots b', which follow the curve of the periphery of said body. Bolts a pass down through cap A and said slots, holding said cap and body together, but allowing the body to be turned so 40 as to present the induction-nozzle C in any one

of a number of different directions. This nozzle extends radially outward from the side of said body. When turned in the position desired, the body B and nozzle C are locked therein by tightening said bolts.

D designates a shaft, which extends transversely across the top of said body B and turns in bearings A' of cap or cover A. It has a draft-regulator, d, fast upon it, this regulator being approximately triangular in cross-section and turning with said shaft under a central opening, A², of said cap. When one of the equal sides of the triangle is turned uppermost, the draft is cut off. When one of the intervening apices of the triangle is uppermost, the draft is at its maximum.

A rod, E, extends transversely through the lower part of B, the body, and is provided at its ends with handles e. To one of these handles a cinder-slide, F, is rigidly secured, 55 extending under the bottom of the body B in a plane parallel to said rod and fitting tightly against said body when in position to close the same. By pulling one of said handles or pushing the other said slide may be removed laterally from the bottom of the body, allowing cinders to fall from within it. The reverse motion of course returns said cinder-slide to its normal position.

Having thus described my invention, what I 75 claim as new, and desire to secure by Letters Patent, is—

In a tuyere iron, a fixed cap, in combination with a body having curved slotted flanges, bolts passing through said slots and connecting said body to said cap, and a nozzle extending from the side of said body and movable therewith, substantially as set forth.

In testimony whereof I affix my signature in presence of two witnesses.

HENRY B. KEIPER.
